US00D862187S

(12) **United States Design Patent** (10) Patent No.: **US D862,187 S**
Borras Marques (45) Date of Patent: **** Oct. 8, 2019**

- (54) **CIRCULAR SAW**
(71) Applicant: **GERMANS BOADA, S.A.**, Rubi (ES)
(72) Inventor: **Cristina Borras Marques**, Rubi (ES)
(**) Term: **15 Years**
(21) Appl. No.: **35/505,896**
(22) Filed: **Oct. 1, 2018**

(80) **Hague Agreement Data**

Int. Filing Date: **Oct. 1, 2018**
Int. Reg. No.: **DM/103160**
Int. Reg. Date: **Oct. 1, 2018**
Int. Reg. Pub. Date: **Oct. 19, 2018**

(30) **Foreign Application Priority Data**

- Apr. 27, 2018 (EM) 005251139-0001
(51) LOC (12) Cl. **08-03**
(52) U.S. Cl.
USPC **D8/66**
(58) **Field of Classification Search**
USPC D8/66
